UNITED STATES PATENT OFFICE.

ALEXANDER W. WALKER, OF BOSTON, MASSACHUSETTS.

SPRING ARCH-SUPPORT FOR SHOES.

No. 892,386.

Specification of Letters Patent.

Patented June 30, 1908.

Application filed September 5, 1907. Serial No. 391,427.

To all whom it may concern:

Be it known that I, ALEXANDER W. WALKER, of Boston, in the county of Suffolk, and State of Massachusetts, have invented 5 certain new and useful Improvements in Spring Arch-Supports for Shoes, of which the following is a specification.

This invention relates to spring arch supports for shoes.

10 More particularly it relates to springs inserted in the soles of boots or shoes for stiffening the arch and for retaining and supporting the shank of the shoe in proper form, to suit the needs of the wearer throughout the life of 15 the shoe.

It is one of the objects of the invention to provide a composite arch support having an elastic flexibility more accurately adapted than previous devices to the assistance of the 20 human foot in the act of walking and to its support when standing. These objects are accomplished by the device hereinafter described and represented in the accompanying drawings, in which:

25 Figure 1 represents part of a shoe in side elevation and in section, equipped with a composite spring embodying the invention. Fig. 2 represents a plan view of the spring represented in Fig. 1. Fig. 3 represents a 30 side elevation of the same spring in section when flexed as in the act of walking, somewhat enlarged. Fig. 4 is a plan of one of the sections of the spring shown in Fig. 2. Fig. 5 is a side elevation of a different form of the 35 spring in section, enlarged. Fig. 6 is a side elevation of the same section, expanded, with the expansion somewhat exaggerated. Fig. 7 is a plan of a detail of the form shown in Figs. 5 and 6.

40 Referring to the drawings: In Fig. 1, 1, represents the inner sole and 2 the outer sole of a shoe. The spring embodying the present invention is set between them. As shown more clearly in Fig. 2, this spring 45 comprises a plurality of thin spring steel plates marked respectively 3, 4, 5, 6 and 10. The shape of the successive sections is shown best in Fig. 3 at 4 or 5. Such a section has a tongue 4' which is struck from the material comprising the plate and is set out slightly from the surface thereof. At the end of this tongue a rivet 4" attaches it to the next plate 5 which in turn has a tongue 5' and a rivet 5" attaching it to plate 6. In similar manner 55 the plate 3 has a tongue 3' attached by a rivet

3" to plate 4. Each successive plate laps its predecessor a little, and the tongue joining it thereto runs in what may be called a reverse direction from the end of the plate.

In Fig. 3, the tongue of the shank plate 3 60 is represented as stiffened by an additional plate 7, and these two plates are covered by a plate 8 which is riveted to the whole at 8". Two small washers 8' are strung on this, allowing the tongue 3' and its attached parts 65 to have a limited up and down play. A convenient shape for the stiffening spring 7 is shown by the dotted line in Fig. 2, and part of this line also outlines the shape of the tongue 3'. At the rear end of shank plate 3, 70 is a similar tongue 9 fastened by a rivet 9" to a plate 10 which has a hole 11 for passage of a screw or nail in the heel of the shoe. Fig. 3 represents the form this composite spring 75 might take if incased in the shoe as represented in Fig. 1, when the wearer is in the act of taking a forward step with the other foot. At that time the person's weight rests upon the ball of the foot, the heel is raised from the ground and the arch of the foot is sustained 80 by the tension of ligaments connecting the front and back portions of the arch. Under these circumstances it is desirable to have the sole of the shoe press gently upward and sustain the arch. If the sole be rigid the 85 effort of rising upon the ball of the foot comes wholly upon the arch of the foot and its ligaments; but with the composite spring shown here the heel is assisted in rising and a part of the stress is borne by the spring, which tends 90 to expand elastically from its compressed condition when the wearer's weight rests with his foot flat upon the ground. This is caused by the elasticity of the various tongues 95 of spring metal. These are set somewhat out from the body of the plates. When the weight of the wearer is upon them they are pressed toward the plates as shown in Fig. 1, but when relieved of this weight, and especially when the heel is raised, the toe remaining 100 down, they tend to spring into their normal positions as shown in Fig. 3.

It is not necessary to have as many sections of the spring as are shown in Figs. 1, 2 and 3. A form of the invention is shown in Fig. 5, in which there is one toe and one heel section in addition to the shank portion. The construction is also somewhat different in that figure. Instead of the tongues being integral with their adjacent plates they are 105 110

separate spring pieces riveted thereto, each plate having a hole punched over its tongue to allow play room therefor, thus forming a recess to receive the tongue when the spring is compressed. In Fig. 5, another feature of the invention is also shown, a reinforcing spring 12, fastened on the under side of shank plate 13 and underlapping the edge of the toe section 14. This stiffens the elastic support of the rear edge of this toe section and adds its effect to the effect of the spring tongue of 18. In like manner the rear part of this plate 12 reinforces tongue 19. This plate 12, therefore, makes it possible in the commercial manufacture of springs embodying the invention to make the main portions of spring steel of uniform gage and flexibility, and yet, to produce springs whose total elastic effect is of any desired degree of stiffness by the selection of suitable reinforcing plates 12, choosing these plates according to the degree of stiffness desired, or omitting the plate 12 altogether if desired.

In both types of the spring, plate 8 is represented covering the topmost plate 3 or 13. This thin plate may have a reinforcing effect upon that plate if desired. The plates may be made of very thin, light, metal.

The invention is not limited to the particular shape of plates and tongues shown and the construction may be varied in other particulars without departing from the spirit and scope of the invention.

I claim:

1. In combination with a shoe, a composite spring within the sole thereof, comprising a plurality of plates, and spring strips intervening between adjacent plates and joining them.

2. The combination of a plurality of overlapping thin plates with an elastic strip at the lap, said strip joining the end portions of the plates which lap each other.

3. The combination of a plurality of overlapping thin plates with an elastic strip fast to both plates which lap; there being a recess in one of these plates adapted to receive said strip.

4. The combination of a plurality of overlapping thin plates with an elastic strip at the lap, said strip joining the end portions of the plates which lap each other; and a reinforcing spring fast on one of the plates and laps outside the remote end of said strip.

5. In combination with a shoe, a composite spring within the sole thereof comprising a plurality of plates, and springs intervening between adjacent plates normally expanding the thickness of the composite structure.

In testimony whereof I hereto affix my signature, in presence of two witnesses.

ALEXANDER W. WALKER.
